UNITED STATES PATENT OFFICE.

AUSTIN D. EBERLY, OF SPOKANE, WASHINGTON.

OIL-TESTING DEVICE.

Application filed February 14, 1920. Serial No. 358,794.

To all whom it may concern:

Be it known that I, AUSTIN D. EBERLY, a citizen of the United States, and a resident of Spokane, in the county of Spokane and State of Washington, have invented certain new and useful Improvements in Oil-Testing Devices, of which the following is a specification.

My invention relates to improvements in oil testing devices and has for one of its objects to provide a device of the character described which shall accurately determine the lubricating qualities of oils when subjected to heat.

Another object is to provide a device of the character described which shall show the relative adhesive qualities of oils with respect to given surfaces when subjected to heat.

A further object is to provide a device of the character described whereby the conditions actually met with in the use of lubricating oil between heated surfaces will be reproduced in my oil testing device and so enable the operator to observe the performance of oil under a reproduction of working conditions.

A further object is to provide a device of the character described which is so constructed that, while comparatively delicate tests may be made, it does not require expert knowledge of oil nor an expert workman to perform the tests.

A further object is to provide a device of the character described which shall be sturdy and cheap of construction.

A still further object is to provide a device of the character described which may be made portable in form, and maintained in adjustment so that it may provide an operator with an ever present and immediately accessible means for testing oils. In this direction, the testing device is especially adaptable for motorists, enabling them to determine the quality of oil before purchasing same.

Still further objects and features of the invention will be described in connection with the accompanying drawings and will be more particularly pointed out in and by the appended claims.

In the drawings:

Figure 1 is a top plan view of the testing device with the cap member removed.

Figure 2 is a perspective view of the cap member. 55

Figure 3 is a side elevation of the testing device showing the cap member in initial position.

Figure 4 is a view similar to Figure 3 but showing the cap member in changed positions. 60

Figure 5 is an enlarged section on line 5-5 of Figure 1.

Figure 6 is an enlarged section on line 6-6 of Figure 1. 65

Figure 7 is an enlarged section on line 7-7 of Figure 1.

Figure 8 is a plan view of a heating unit preferably used in connection with my device. 70

Figure 9 is a view in side elevation of the heating unit.

Figure 10 is a top plan view of the heating unit.

Like numerals of reference designate corresponding parts throughout the various figures of the drawings. 75

At 10 I have generally indicated a supporting member comprising side walls 11 and 12, end wall 13 and flange 14. In the particular embodiment of the invention disclosed I have constructed the member 10 of metal capable of conducting electricity but it will be understood that I do not wish to limit myself to this construction. The forward end of member 10 is provided with a depending, pointed lug 17 disposed centrally of end wall 13, while the rear end of member 10 is supported by the leveling screws 18 and 19, disposed on the bottom edges of side walls 11 and 12, respectively. Hinged to flange 14 by pin 20 is the metal platform 21. 85

Supporting member 10 is provided with a level indicating bubble container at 15, while a second level indicating bubble container is provided on the platform 21 at 16. 95

Secured to side wall 12 by rivets 22 is a worm gear segment 23, the pitch circle of said segment being taken from the pin 20 as a center. Meshing with segment 23 is the worm 24 secured to the shaft 25 which is journaled within the platform 21 at 26, and the upper end of shaft 20 carries the knurled nut 27. The collar 28 pinned to shaft 25 at 29 serves to limit shaft 25 to revoluble move- 100

ment. It will be seen that by manually revolving nut 27, the platform 21 and all members secured thereto may be tilted radially with respect to the pin 20 and thus give the operator power to regulate the degree of incline between the platform 21 and the horizontal.

On the side wall 11 is provided a scale 11' preferably divided into degrees of a circle. 19 A pointer 21' is suspended from platform 21 and in conjunction with the scale 11' will serve to indicate the degree of incline of platform 21 and members carried thereby.

A base member 30, preferably having its 15 upper and substantially plane face 31 ground to a relatively smooth, flat finish, is provided with a depending, peripheral flange 32 and a centrally disposed depending leg 33. Leg 33 is bored and internally 20 threaded as at 34 to accommodate screw 35 which serves to hold base member 30 rigidly with respect to platform 21 and to maintain the surface 31 in parallel relation with the platform 21.

25 A heating unit indicated generally at 36 is positioned within the recess 30' formed on the under side of member 30 by flange 32. Spring collar 37, which frictionally grips the leg 33, serves to hold the heating unit 30 36 in position shown in Fig. 7.

The heating unit 36 consists of metallic plate 38, a thermostat generally indicated at 39 and heating element 40, there being a sheet of asbestos 42 and a sheet of insulating material 41 interposed between the plate 38 and the heating element 40. While the heating element 40 may be of any suitable type, I have shown a coil of high resistance wire for the purpose. Between 40 the heating element 40 and the base member 30 is interposed a sheet of insulation 43 which may be pierced as at 44 to allow the free passage of heat from said element to said base. One end 45 of the heating element 45 40 passes through the insulation 41, asbestos 42 and plate 38 as at 46, and is attached to the binding post 47 which is grounded to the plate 38. The other extremity 48 of heating element 40 passes through 50 insulation 41, asbestos 42 and plate 38 and is insulated from plate 38 at 49. Extremity 48 is attached to terminal 50 which is secured to but insulated from plate 38 at 51.

Attached to terminal 50 is thermostat 39. 55 While any adaptable form of thermostat may be used, I have shown for the purpose a thermal spring made up of two metal strips 52 and 53 having different heat coefficients. Spring 52 carries the contact point 60 54 which normally contacts with point 55 carried by terminal 56. Terminal 56 is secured to plate 38 by rivet 57 and is insulated therefrom at 58. One extremity of wire 59 is secured to terminal 56 while the other extremity is led down through an

aperture 60 provided in platform 21 and then attached to binding post 61 on a current indicator 62. Indicator 62 is secured to platform 21 which is cut away and glassed over as at 63 (Fig. 1) so as to allow the operator to watch the action of said indicator. Indicator 62 may be of any suitable type and need only show whether or not electric current is passing therethrough. The type shown in the drawings represents 75 that consisting of a varied colored cylinder, the particular color exposed to the operator's view indicating either the passage of electricity or a broken circuit.

From the binding post 63 on the indicator 80 62, a wire 64 leads to the binding post 65 secured to the wall 13 and insulated therefrom by insulating washers 66. A binding post 67 is also secured to wall 13 and is grounded thereto.

The operation of the heating unit 36 is as follows: A wire 68 leading from a source of electricity (not shown) is attached to binding post 65, while a wire 67' is attached to the binding post 67 and leads 90 back to the source of electricity. Electricity may then flow through the following path, wire 64, current indicator 62, wire 59, terminal 56, wire end 48, heating element 40, wire end 45, terminal 47, metallic plate 95 38, collar 37, leg 33 and thence through the platform 21 and supporting member 10, binding post 67, wire 67' back to the source of electricity. The electric current, in passing through element 40 will generate heat 100 which serves to heat the entire base member 30 and particularly the surface 31. The bulk of the heat from element 40 will be deflected upwardly by means of the asbestos sheet 42. The thermostat 39 is so constructed 105 that when the base member 30 and the cap member 69, to be described, reach a predetermined degree of heat, the heat caused thereby within the recess 30' will be sufficient to warp the thermal spring consisting 110 of strips 52 and 53 so as to separate contact points 54 and 55 and interrupt the flow of electricity through element 40. When the heat drops below the predetermined degree 115 the circuit will be closed again by the natural spring tendency of the thermal spring 39. A set screw 70 (Fig. 8) which is threaded through bracket 71 serves to regulate the thermal spring 39 by varying the tension thereof. Bracket 71 is secured to and 120 insulated from plate 38.

As long as current is flowing through element 40, the current indicator 62 will so indicate. However, when the heat of base element 30 reaches the predetermined degree, 125 at which time the operator is to take certain steps in the test, the thermostat 39 will break the circuit as described above thus causing the indicator 62 to register the fact of a broken circuit and notifying the op- 130

erator to proceed with his test. Since it has been shown by actual test that a predetermined degree of heat as high as 300 degrees, Fahrenheit, may be reached in approximately two minutes on six volts and four amperes when the heating element 40 is of the approximate size shown in Figure 10, it will be seen that it is possible for a motorist to use the testing device by plugging into an automobile's storage battery circuit through a lamp socket. In case an ammeter is provided on the instrument board of the automobile, the current indicator 62 may be dispensed with since the ammeter will then serve to indicate the flow and interruption of flow of electricity through element 40.

I provide a cap member in the form of a plate 69 made of metal and ground flat and smooth on the surface 72 to correspond with the surface 31 of base member 30. Secured to plate 69 is a handle 73, preferably constructed of a nonmetallic material.

Pivoted to the under side of platform 21 by means of shaft 74 supported by brackets 75 (Fig. 6) are the depending legs 76 of the cap positioning clip 77. Clip 77 is preferably forked to form upwardly extending arms 78 which are adapted to normally bear against the base member 30 as at 79. The upper extremities of arm 78 project upwardly above surface 31 of member 30 to normally hold cap 69 in the position shown in Figure 3. Clip 77 is normally held in the position shown in Figure 3 by means of the extension 80 (Fig. 7) the end of which is adapted to engage the notch 81 provided in spring 82. Spring 82 is secured to platform 21 at 83 and is provided with a second notch 83'. Clip 77 is provided with a handle 84.

The principle and operation of the device is as follows: The value of oil as a lubricant is dependent upon its ability to adhere to surfaces and the cohesion among its own particles. The greater the adhesion to surfaces and the less the cohesion among its own particles the more ideal is the oil for lubricating purposes. When heated, the body of oil is more or less broken up according to the grade of the oil and as the temperature rises this breaking up of the body lowers the oil's power of adhesion to surfaces and consequently lowers the value of the oil as a lubricant. Given two oils, one a relatively good lubricant and the other a relatively poor lubricant, the first will have such body that a given applied heat will not break up the body enough to destroy its adhesive qualities. The same heat applied to the second oil will so break up its body that its power of adhesion to surfaces is lost and its value as a lubricant is gone.

In my testing device I may reproduce approximately the conditions under which an

oil is actually expected to work and hence am able to observe the performance of the oil under these conditions. For instance, assuming that I am desirous of testing for relative qualities two lubricating oils to be used in the cylinders of a gas engine. It would then be preferable to construct the base member 30 and cap member 69 of cast iron. The surfaces 31 and 72 would be ground to approximately the same smoothness as that of the cylinder bore.

Leveling screws 18 and 19 are first adjusted to bring the platform 21, and hence surface 31, level, and the position of pointer 21' with respect to the scale 11' is noted. Then a few drops of the first oil are placed on surface 31 and the cap 69 set in the position shown in Figure 3 and pressed downwardly until the oil is spread in a thin film between the surfaces 31 and 72. The heating element 40 is then introduced into an electric circuit by properly connecting binding posts 67 and 68 to a source of electricity, as above described. The temperature of member 30 and cap 69 will then be raised by the heat generated by element 40, and the confronting surfaces 31 and 72 will thus be heated. Cap 69 is heated by absorbing heat from member 30 as soon as indicator 62 shows that the electric circuit has been broken by thermostat 39 and that therefore the predetermined degree of heat has been reached, handle 84 is depressed throwing clip 77 into the position of Figure 4. The end of extension 80 (Fig. 7) will then be engaged by spring 82 at notch 83' and will be held thereby in the position of Figure 4.

Nut 27 is then revolved to slowly incline or tilt platform 21 and hence surface 31 thus causing surface 31 to function as an inclined plane. When cap 69 slides downwardly, as shown in Figure 4, the operator will note the degree of incline as registered by pointer 21' on scale 11'.

The surfaces 31 and 72 will then be thoroughly cleansed and the operation repeated with the substitution of the second oil for the first. The oil which allows cap 69 to slide downwardly with the least amount of incline to surface 31 is the better oil as it shows that the applied heat has least affected its adhesive qualities since a lesser amount of gravity is called upon to cause cap 69 to slide. A considerable or entire loss of adhesive qualities would allow the weight of cap 69 to squeeze the film of oil out from between surfaces 31 and 72 and thus proportionately destroy the lubricating function of the oil, whereupon the friction between surfaces 31 and 72 would prevent cap 69 from sliding downwardly.

Having by experimentation, as above, determined the best oil for a given purpose, it is then possible to make a tester for that particular purpose in which the degree of

incline of surface 31 is fixed. In this case the hinging of platform 21, the worm mechanism for tilting platform 21, pointer 21', scale 11', and level indicator 16 may be eliminated. For instance, having determined that with a certain degree of incline a proper oil for a certain purpose will allow cap 69 to slide downwardly, while a poor oil for the purpose will not allow this sliding movement, a tester may be constructed to hold base member 30 and hence surface 31 at this particular degree of incline. In this case a level indicator 16' is preferably secured to side 11 to allow for the horizontal leveling of the supporting frame 10.

Having, now, an oil to be tested for the certain purpose, a sample of the oil is placed between the surfaces 31 and 72 as before, the clip 77 holding the cap 69 from sliding downwardly. The element 40 is then caused to heat the base member 30 and cap 69. When indicator 62 shows the proper heat has been reached the handle 84 will be depressed, freeing arms 78 from contact with base member 30. If cap 69 slides down it is proof that the sample is suitable for the purpose intended, while if the cap 69 fails to slide down it is proof that the oil's body will not stand up under heat and that it is therefore unsuited for the purpose intended.

While I have shown and described particular embodiments of my invention, I do not wish to be limited thereto except for such limitations as the claims may import.

What I claim is:

1. A device for testing oils comprising a base member having an inclined and substantially plane upper surface, a cap member adapted to slide by gravity on said inclined surface, an electric heating element adapted to heat said base member and said cap member, and thermostatic means controlled by the temperature of said base member and said cap member and adapted to control said heating element.

2. A device for testing oils comprising a base member having an inclined and substantially plane upper surface thereon, a cap member adapted to slide by gravity on said inclined surface, an electric heating element adapted to heat said upper surface, thermostatic means adapted to control said heating element, and indicating means controlled by the flow of electricity through said heating element and adapted to indicate when said heating element has heated said upper surface to a predetermined degree of heat.

3. A device for testing oils, comprising a base member having an inclined surface provided thereon, a cap member having a surface adapted to confront said inclined surface, said cap member being adapted to slide down said inclined surface, means adapted to heat said confronting surfaces, means

adapted to initially hold said cap member from sliding down said inclined surface, and means adapted to retract said holding means to allow said cap member to slide down said inclined surface.

4. A device for testing oils, comprising a base member having an inclined surface provided thereon, a cap member having a surface adapted to confront said inclined surface, said cap member being adapted to slide down said inclined surface, means adapted to heat said confronting surfaces, means adapted to indicate when said confronting surfaces have reached a predetermined temperature, means adapted to initially hold said cap member from sliding down said inclined surface, and means adapted to retract said holding means to allow said cap member to slide down said inclined surface.

5. A device for testing oils, comprising a base member having an inclined surface provided thereon, a cap member having a surface adapted to confront said inclined surface, said cap member being adapted to slide down said inclined surface, means adapted to heat said confronting surfaces, means adapted to automatically control said heating means and thereby control the temperature of said confronting surfaces, and means adapted to position said cap member on said base member until said confronting surfaces have reached a predetermined temperature.

6. A device for testing oils, comprising a base member having an inclined surface provided thereon, a cap member having a surface adapted to confront said inclined surface, said cap member being adapted to slide on said inclined surface, means adapted to heat said confronting surfaces, means adapted to position said cap member on said inclined surface until said surfaces have reached a predetermined temperature, and means adapted to indicate when said confronting surfaces have reached said predetermined temperature.

7. The method of testing oils comprising the application of a film of oil between the confronting surfaces of an inclined plane and a slidable cap positioned thereon, heating of said inclined plane and said cap, and holding said cap from sliding down said inclined plane until the said confronting surfaces have reached a predetermined temperature.

8. The method of testing oils comprising the application of a film of oil between the confronting surfaces of an inclined plane and a slidable cap positioned thereon, heating of said confronting surfaces and holding said cap from sliding down said plane until said confronting surfaces have reached a predetermined temperature, and the release of said holding means when said pre-

determined temperature has been reached.

9. The method for testing oils comprising the application of oil between the confronting surfaces of a base member and a cap member, the initial plane of said confronting surfaces being horizontal, heating of said confronting faces, and gradually in-

clining said base to determine the amount of incline necessary to cause said cap to slide down said inclined plane. 10

In testimony whereof, I hereby affix my signature.

AUSTIN D. EBERLY.
